(No Model.)

G. W. WILLIAMS.

BLIND STOP.

No. 379,748.

Patented Mar. 20, 1888.

UNITED STATES PATENT OFFICE.

GEORGE W. WILLIAMS, OF BROOKLYN, NEW YORK.

BLIND-STOP.

SPECIFICATION forming part of Letters Patent No. 379,748, dated March 20, 1888.

Application filed September 10, 1887. Serial No. 249,367. (No model.)

To all whom it may concern:

Be it known that I, GEORGE W. WILLIAMS, of Brooklyn, in the county of Kings and State of New York, have invented a new and Improved Blind-Slat Fastener, of which the following is a full, clear, and exact description.

My invention is an improvement in the class of blind-slat fasteners which consist of an apertured or notched segmental plate, adapted for attachment to either the slats or frame of the blind, and a catch or locking device adapted to engage with the said plate, for the purpose of holding the slats more or less open or wholly closed, as the case may be.

By an improvement hereinafter described and claimed, in the form of a plate and catch having these functions, I am enabled to attach them by means of screws to blinds of the ordinary construction without cutting or otherwise mutilating the latter.

Reference is to be had to the accompanying drawings, forming a part of this specification, in which similar letters of reference indicate corresponding parts in all the figures.

Figure 1 is a front elevation of a pair of blinds having my improvement applied, and Fig. 2 is a longitudinal section on line xx of Fig. 1. Fig. 3 is a partial elevation of a blind, illustrating the slats as held in position to throw the light downward; and Fig. 4 is a section through line yy of Fig. 3. Fig. 5 is a similar section, the blinds being held at right angles to the stiles; and Fig. 6 is a perspective detail view of the device.

In carrying out the invention, a segmental plate, A, having an integral base, B, at right angles thereto, is provided, and in this plate a concentric series of apertures, b , is made side by side, at equal distances apart, near the outer curved edge of the plate. The apertures b are preferably rectangular in shape and are radially arranged, whereby the united upper and lower ends of the apertures each constitute an arc, concentric with the semicircular edge of the plate.

The lower edge of the segmental plate A is straight, and the lower edge of the base B is made to align with the aforesaid edge. The upper edge of the plate extends beyond the line of the base, whereby the upper aperture and the upper end portion, b' , of the plate are made to project beyond the edge of the slat when the plate is secured to the blind.

In attaching the plate, all the slats being

loosely connected by a bar attached to their inner edges in the usual way, it is secured by means of the base B to the end of the central slat, D, or to any convenient slat of the blind, so as to project outward at right angles from the blind and partially beyond the inner edge of the recessed stile C, or the stile adapted to engage the stile of an opposing frame. When the plate is attached to a blind opening to the left, a left-hand plate must be employed, and vice versa.

Upon the stile C an angular lever, E, is pivoted at the intersection of its two members, e and e' , the position of the vertical member e with relation to the plate being such that a lip, f , integral with and extending from its end at the inner side, will, when the slats are closed, enter the lower aperture of the plate and retain the slats in position. The lip f tapers slightly upward, so that when it enters the aperture of the plate it wedges therein and prevents play of the slat. The horizontal member of the lever E is provided with a finger-plate, f' , by which construction and arrangement the lip f is held by gravity in engagement with the apertured plate A.

In operation, when it is desired to hold the slats at right angles to the stile, or fully open, the lever is made to engage the upper aperture, and by the engagement of the lever with the intermediate apertures in the plate the slats may be held at various inclinations.

In Figs. 3, 4, and 5 the slats are shown as held in different positions.

Having thus described my invention, what I claim as new, and desire to secure by Letters Patent, is—

An improved blind-slat fastener consisting of the segmental plate A, provided with a series of radially-arranged apertures, b , near the outer curved edge and having an apertured base, B, at right angles thereto for securing it to a blind-slat, and the angular gravity-lever E, apertured at its angle for pivoting it to the stile and provided with the upwardly-tapering lip f , extending from the end of the member e , and the finger-plate f' , projecting laterally from the member e' , substantially as herein shown and described.

GEORGE W. WILLIAMS.
